UNITED STATES PATENT OFFICE.

WILLIAM PERRY AND JAMES A. PRINCE, OF INDIANAPOLIS, INDIANA.

BROOM-COVER.

SPECIFICATION forming part of Letters Patent No. 313,233, dated March 3, 1885.

Application filed December 31, 1883. (No model.)

To all whom it may concern:

Be it known that we, WILLIAM PERRY and JAMES A. PRINCE, both of the city of Indianapolis, county of Marion, and State of Indiana, have invented certain new and useful 5 Improvements in Broom-Covers, of which the following is a specification.

Our said invention consists in an open-ended sack adapted to be slipped over a package of brooms, and provided with draw-strings 10 at each end, by which its ends can be drawn in and the straw portion of the brooms thus efficiently protected.

Referring to the accompanying drawings, 15 which are made a part hereof, and on which similar letters of reference indicate similar parts, Figure 1 is a perspective view of a stand of brooms covered or secured by our improved cover; Fig. 2, a perspective view 20 of the cover; Fig. 3, a transverse section of the same, and Fig. 4 a cross-section thereof.

In said drawings, the portions marked A represent the sack or cover, B the brooms, and a' c the draw-strings. The sack or cover 25 A is preferably made of paper, although it may be made of muslin or other fabric, and is of sufficient size to contain the desired number of brooms, (usually a dozen.) Its upper edge, a, is preferably turned in and provided 30 with holes b, and the lower edge, g, is likewise turned in and provided with holes d. The draw-strings a' c are passed through these holes and adapted to draw up the sack or cover, as will be presently more fully de-

scribed. The brooms B are usually secured 35 together in bunches of a dozen and the cover A slipped over the straw portion. The draw-string a' is drawn up, so as to bring the upper edge of the cover closely around the top of the broom, and the string c is likewise drawn 40 in at the bottom, so that the brooms are completely protected by the cover, as will be readily understood. This cover prevents the straws from becoming broken or the bottoms of the brooms from being spread out while said 45 brooms are being handled or transported in the course of trade.

Having thus fully described our said invention, what we claim as new, and desire to secure by Letters Patent, is—

1. A cover for brooms, consisting of a sack 50 open at both ends, and provided with draw-strings at each end, substantially as set forth.

2. A cover for brooms, consisting of an open-ended sack having turned-in portions and 55 perforations at each end, and draw-strings passing through said perforations, whereby the ends are adapted to be drawn in around the brooms at the top and bottom, substantially as set forth.

In testimony whereof we affix our signatures in presence of two witnesses.

WILLIAM PERRY.
JAMES A. PRINCE.
